UNITED STATES PATENT OFFICE.

CLARK CUPPET, OF GLADE FARMS, WEST VIRGINIA.

SURVEYING-INSTRUMENT.

SPECIFICATION forming part of Letters Patent No. 236,308, dated January 4, 1881.

Application filed June 18, 1880. (No model.)

To all whom it may concern:

Be it known that I, CLARK CUPPET, a citizen of the United States, residing at Glade Farms, in the county of Preston and State of West Virginia, have invented certain new and useful Improvements in Surveying-Instruments; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 My invention relates to improvements in surveyors' instruments; and its object is to combine in one instrument means of indicating the distances and ascertaining the measurements of heights and plane surfaces without the aid 20 of a surveyor's chain. I attain these objects by the apparatus illustrated in the accompanying drawings, in which—

Figure 1 represents, in elevation, the front side of the instrument. Fig. 2 is a top plan 25 thereof. Fig. 3 represents the rear side of the instrument in elevation, some portions being broken away to better illustrate the positions of other parts.

The same letters of reference are used in all 30 the figures in the designation of identical parts.

A is the base-plate of a frame, composed of the parts A A' A' and A² A², which is adapted to be placed at a upon the ordinary tripod used 35 by surveyors for holding a compass and telescope. A' A' are slotted segmental arms, bolted at their lower ends to the base-plate at b and at their upper ends to inclined upright standards A² A². The standards A² A², secured at their upper ends to the segmental arms, are bolted at their lower ends to the base-plate A. The segmental arms A' A' have slots 40 c extending nearly their entire length.

B is a movable segmental rack-bar provided 45 with lugs d d' d', which project from the opposite sides thereof and are adapted to slide in ways formed by the slots c.

C is a thumb-wheel located upon the outer side of the arm or brace E, which is secured 50 at one end to the rear segmental arm, A', and at the other end to the rear standard, A². At-

tached to the arbor of wheel C, and located between the arms A' A', is a pinion, C', meshing with the rack-bar B. To the inner end of the arbor of the thumb-wheel, and within the 55 dial-box F, is attached the driver of an internal-toothed gearing, hereinafter described. The thumb-wheel is operated to move the rack-bar up and down between the segmental arms, and at the same time to move the train of 60 toothed gearing in the dial-box.

D is a telescope such as ordinarily used in surveying-instruments, provided internally with the usual cross-hairs or "cobwebs." It is pivoted at one end between the arms e, 65 which are secured to the base-plate A, and is at the opposite end secured to the rack-bar B by suitable means. By this means the outer end of the telescope may be raised and lowered to any point on the segmental arms in 70 range with the desired object.

F is a dial-box, the back of which is fixed to the front segmental arm, A', at f f'.

G, g, H, I, i, K, k, and J are respectively spur-wheels and pinions, forming a train of 75 gearing in the inside of the dial-box F. G is the main wheel or driver, secured to the spindle of the thumb-wheel C, to which spindle is also secured the pinion g. The pinion g imparts motion to the spur-wheel H, whose spindle projects through the face of the dial-box and carries the main index-finger H', for marking the degrees on the large dial. The spur-wheel or driver G meshes with and imparts motion to the pinion i, whose spindle projects 80 through the face of the dial-box and carries the index-finger I', for marking the minutes on the dial I'. This index-finger I' makes an entire circuit of its dial while the index-finger H' is being moved one space on the large dial. 85 In other words, the finger I' records sixty minutes (60') for every degree (1°) that is recorded by the finger H'. The second ("') finger J' is mounted on the spindle of the pinion J of the train of gearing, and makes one circuit of its dial J' while the minute-finger I' is being moved to mark one division of its dial. 90

A spirit-level, P, is secured to the top of the telescope.

The operation of the instrument for measuring distances is as follows: After the bearings are found, in the usual way, with the

compass, the instrument, which may be termed an "indicator," is placed on the tripod. In the normal condition of the instrument the telescope is level and the index-fingers of the respective dials point at zero. Having placed the staff at any desired point distant from the instrument, the open end of the telescope is raised by turning the thumb-wheel C until the cross-hairs of the telescope are brought in range with the top line of the staff. The hands of the respective dials will then indicate the degrees, minutes, and seconds passed over, and by reference to an established table of distances with which the graduations of the dials are arranged the exact distance from tripod to staff may be ascertained. Thus may the dimensions of the sides of triangles and other measurements of distances made in ordinary surveying, and the results deduced therefrom, be quickly and easily determined. In measuring heights the staff should, for convenience, be placed either to the right or left of the object to be measured, and as nearly opposite as possible to its central perpendicular line. The telescope should first be raised to a certain angle—say $22^{\circ} 30'$. It is then to be directed to the zero of the staff, then to the top line of the staff, and the measurement indicated by the dials noted. The telescope is then reversed and directed to the base of the object to be measured, and from that point to the top line of the object, and the latter measurement in degrees, minutes, and seconds also noted. These respective measurements will 35 form the first two terms of a proportion and

the length of the staff a third term, which, when reduced, gives the desired height. For instance, if the measurement of the staff is $2^{\circ} 30' 15''$, the measurement from the base of object to the top line of the object $20^{\circ} 15' 30''$, and the length of the flag-staff is ten feet, the following proportion is had: $2^{\circ} 30' 15'' : 20^{\circ} 15' 30'' :: 10 : x$, the required height. 40

The operation of the instrument above described is modified by the following condition: 45 Where the zero of the staff and the base of the desired height are on a level the telescope need not be redirected to the zero of staff after the distance from the zero of the staff is obtained.

To facilitate the calculations I prefer to number the dials both from right to left and from left to right, thus providing two sets of numbers for each dial. 50

Having thus described my invention, what 55 I claim, and desire to secure by Letter Patent, is—

In a surveyor's instrument for measuring heights and plane surfaces, the combination of the slotted segmental arms, the rack-bar, 60 and graduated dials with a telescope and level, constructed and operated substantially as described.

In testimony whereof I affix my signature in presence of two witnesses.

CLARK CUPPET.
